UNITED STATES PATENT OFFICE.

TONY NARODA, OF WHITING, INDIANA.

SHOE-LACE-CUTTING DEVICE.

1,411,294.

Specification of Letters Patent. Patented Apr. 4, 1922.

Application filed January 29, 1921. Serial No. 440,860.

To all whom it may concern:

Be it known that I, TONY NARODA, citizen of Russia, residing at Whiting, in the county of Lake and State of Indiana, have invented 5 certain new and useful Improvements in Shoe-Lace-Cutting Devices, of which the following is a specification.

This invention relates to a device for cutting a sheet of material into one continuous 10 strip, being intended more particularly for use in cutting leather shoe-laces, or leather strips for other purposes.

The invention has for an object to provide a simple and inexpensive device of the kind 15 stated which will cut the strip of uniform width and which will be further characterized by ease of manipulation and rapidity of operation.

For further comprehension of the invention, and of the objects and advantages 20 thereof, reference will be had to the following description and accompanying drawings, and to the appended claims in which the various novel features of the invention are 25 more particularly set forth.

Fig. 1 of the drawings is a plan view of a device embodying the invention.

Fig. 2 is a transverse section on the line 2-2 of Fig. 1.

Fig. 3 is a detail plan view of the sheet to 30 be cut, as prepared for insertion in the device.

As here shown my improved device comprises a supporting table 10 which is formed 35 to present a pair of spaced slots 11 extending inwardly from one side thereof, leaving a central prong 12 projecting between them, this prong preferably terminating short of the edge line of the table as shown, while the 40 opposed side walls of the slots are preferably narrowed in toward one another at their outer end portions as at 11'.

Extending inwardly from one side of the prong 12 is a notch or recess 13 which opens 45 into the slot, this recess accommodating a knife 14 which cuts the strip of leather from the main body thereof. This knife as here shown comprises a vertically disposed blade whose cutting edge faces toward the outer 50 end of the prong 12, and which is fixed at its upper end on a lever arm 15. This arm is fulcrumed at its inner end as at 16 to the prong 12 and is provided at its outer end with a handle 17 for adjustment.

55 The outer end of this arm 15 projects freely under a serrated strap or yoke 18

which extends transversely of the prong 12 at the outer end thereof and is secured at its ends to the latter, the main body of the yoke being parallel to the surface of the prong 12 60 and spaced therefrom a sufficient distance to permit of vertical movement of the arm 15 so as to bring a lug 19 into or out of engagement with the serrations 20 on the yoke, whereby the arm may be locked in adjusted 65 position. Upon the arm 15 at a point between the yoke 18 and knife 14 are a pair of rollers 21 whose axes are parallel to the arm and which are adapted to rest on the prong 12.

The manner and use of my improved device is as follows: The sheet to be cut into a strip, and which is indicated at 23, has a comparatively small opening 24 first cut in the middle thereof and a short tongue 25 cut in the wall of the opening. The arm 15 70 is then adjusted, by springing the outer end downward and moving it laterally until the lug registers with the correct serration on the yoke 18, to locate the knife 14 at a distance from the inner end of the recess 13 75 corresponding to the width of strip it is desired to cut. The sheet is then placed in position on the device, which is done by moving it longitudinally of the prong 12 with the latter extended through the opening 24, the outer end of the prong extending 80 over the sheet, while the other parts of the table are under the sheet and support the latter, the sheet being finally given a movement to enter the part thereof adjacent the tongue 25 into the notch 13, and the knife 14 85 into the slit between the tongue 25 and the main body of the sheet.

The tongue 25 is then inserted upwardly 90 through the recess 13 between the inner end 95 of the latter and the blade 14. The cutting of the strip is then effected by pulling on this tongue 25 and at the same time giving the sheet a rotary movement, which is done by hand, on the table.

During this operation, as will be apparent, the knife 14 will sever from the wall of the opening 24 a strip 30 of the proper width, the opening constantly enlarging as the operation proceeds. By adjusting the 100 arm 15 the distance between the knife 14 and the end of the recess 13, which forms a gauge, may be varied, with a consequent variation in the width of the strip cut.

As indicated in Fig. 1 I prefer to arrange 110 the table 10 to present a number of these cutting devices or units spaced therealong,

the members forming the outer walls of the slots being in the form of fingers 10', the fingers for each unit being spaced from those of the adjacent units as indicated.

5 It will be noted that with the arrangement of the cutter and guide, working outwardly from an opening in the centre of the material, the knife 14, which is approximately tangential to the opening 24 in the material, 10 points away from said opening so that no tendency exists to cut toward said opening and so sever the lace, while at the same time the guide formed by the end slot 13 prevents the knife from moving tangentially of the 15 opening 24 into the body of the material. It will be noted also that by inserting the pronged element 12 through the opening in the material, a single element acts to hold the material against both vertical and lateral 20 displacement.

Having thus described my invention what I claim as new and desire to protect by Letters Patent of the United States is as follows:

25 1. A device of the class described comprising a table presenting a pair of slots extending inwardly from one edge to leave a prong-like element therebetween, said prong-like element having a notch in one side thereof, 30 an arm pivoted on prong-like element toward the inner end thereof and extending outwardly therealong, a knife fixed to said arm and projecting downwardly into said notch, a pair of anti-friction rollers carried 35 by said arm intermediate the ends thereof and adapted to bear on the said prong-like element during adjustment of the arm, a serrated yoke fixed to the table and under which the arm passes, and a lug on the arm

adapted to engage in any one of the serrations in the said yoke.

2. A device of the kind described comprising a table presenting a pair of slots extending inwardly from one edge and a prong therebetween, said prong being adapted for insertion in an opening in the material being cut, a knife on said prong, and a gauge member on said prong co-operating with said knife, and means for adjustably positioning said knife with respect to said gauge member, said means including an arm pivoted on said prong and having the knife fixed thereto, and co-operating means on said prong and arm for holding the latter in different adjusted positions.

3. A device of the kind described comprising a table presenting a pair of slots extending inwardly from one edge and a prong therebetween, said prong having a notch in one side thereof through which the strip being cut is adapted to be passed upwardly, and a knife extending into said notch, said knife being movable laterally into and out of said notch.

4. A device of the kind described comprising a table presenting a pair of slots extending inwardly from one edge and a prong therebetween, said prong having a notch in one side thereof through which the strip being cut is adapted to be passed upwardly, and a knife extending into said notch, and means for adjustably positioning said knife with respect to the inner wall of the notch, said means being adapted to move said knife laterally into and out of said notch.

In testimony whereof I have affixed my signature.

TONY NARODA.
